UNITED STATES PATENT OFFICE.

EMIL J. HANSEN, OF GREEN BAY, WISCONSIN, ASSIGNOR TO FORT HOWARD PAPER COMPANY, OF GREEN BAY, WISCONSIN, A CORPORATION OF WISCONSIN.

SHEET OF FOLDED MATERIAL.

Original application filed September 12, 1924, Serial No. 737,281. Divided and this application filed November 1, 1926. Serial No. 145,565.

This invention relates to improvements in folded tissue or thin paper sheets, for use as napkins, towels, toilet paper, lunch wrappings and like articles.

5 The subject matter of this application is a division of a co-pending application filed by me on the 12th day of September, 1924, bearing Serial No. 737,281.

10 The primary object of this present invention is the provision of a sheet of material, of this character, wherein the same is folded upon itself in a unique manner, so that the folded article will have a double thickness at the point where the same will be grasped, 15 whether within a dispenser therefor or other container, on its removal therefrom, and also will automatically become partially or completely unfolded, thus eliminating any additional effort for the initial unfolding of 20 the article, when being extracted or drawn from the holder or container, the double thickness being effective to prevent the tearing of the material and giving added strength to the article at the time when the 25 same is required for the successful withdrawal of such article as a unit or unmutilated.

Another object of the invention is the provision of a sheet of material of this 30 character, wherein it is folded in such manner that a double thickness of grasping area is located exteriorly of the folded article along one edge at both sides of the same, so that irrespective of which side of the 35 article is outermost of a stack within a dispenser or holder therefor, the said article can be withdrawn in a quick and convenient manner, without liability of the same being mutilated or torn, and with resultant initial 40 unfolding of such article.

A further object of the invention is the provision of a sheet of material of this character, wherein the folding thereof enables the article to be compact and to insure 45 a single one to be grasped at a time, and in extracting the same for removing it from a suitable dispenser or container in which a superimposed pile or stack of the articles may be placed the article will not become 50 torn or mutilated, as it will be of double ply or thickness at the point wherein the same will be grasped.

A still further object of the invention is the provision of a sheet of material of this

character, wherein the construction thereof is novel and simple, light in weight, durable, neat in appearance, strong, and inexpensive to manufacture.

Other objects will be in part obvious and in part hereinafter pointed out.

The improvements in the details and arrangement of construction will be apparent from an inspection of the accompanying drawings, in connection with the specific description hereinafter contained; and wherein in the preferred embodiment of the invention is disclosed for the purpose of imparting a full understanding of the same.

In the accompanying drawings:

Figure 1, is a plan view of a sheet of material showing the lines along which the same is folded in accordance with the invention.

Figure 2, is a perspective view showing the article completely folded.

Figure 3, is a perspective view illustrating the article partially unfolded when extracted from a pile or stack or taken from the dispenser.

Figure 4, is an enlarged sectional view taken substantially on the line 4-4 of Figure 2.

Similar reference characters indicate corresponding parts throughout the several views in the drawings.

Referring to the drawings in detail, particularly Figure 1, there is illustrated a sheet constituting the blank from which the article is folded in accordance with the invention. This sheet A, of paper or other material to be used as a napkin, towel, toilet paper, lunch wrapping or other article may be of any desired or necessary size and as will be understood of any type or quality of paper or other material, preferably tissue or thin crepe stock.

The sheet A, is primarily folded along the median line 10, which is styled the half fold of such blank, as the halves of the sheet will now be in superimposed relation to each other. Then the half folded sheet is further folded along substantially parallel predetermined lines indicated at 11 and 12, 13 and 14, 15 and 16, and 17 and 18. The lines 11 and 12, are substantial continuations of 100 each other as are the lines 13 and 14, the lines 15 and 16, and the lines 17 and 18. The fold line 19, which is at right angles to all other

fold lines hereinbefore described, is the line on which the article is finally folded.

- When the sheet A, is provided with the fold lines hereinbefore referred to it is divided into a plurality of sections indicated at 20 and 21, 22 and 23, 24 and 25, 26 and 27, 28 and 29, and 30 and 31. As illustrated by Figure 2, of the drawing, the sections 20 and 21, and 30 and 31, in the half folded 10 blank are directly opposite each other, these being folded inwardly at one side of said half folded blank, while the sections 24 and 25, and 26 and 27, which are likewise opposite each other are reversely folded inwardly at the reverse or other side of the half folded sheet. The thus folded sheet in its elongated formation finally folded on the fold line 19, presents double ply or thickness grasping tabs B, the combined 20 width of which transversely to the fold is approximately equal to or slightly less than the width of a dispenser cabinet in which the articles are adapted to be received. Preferably, each tab B, has a width which may 25 be equal to or slightly greater than one-half the transverse width of the folded article, and therefore in forming the tabs both tabs combined will equal to the width of the article when thus folded.
- 30 The tabs B, are on opposite sides of the folded article and of double thickness, it being of course understood that they may be of any desired and predetermined width, and co-extend with the outside edges of the 35 folded sheet.
- It will be noted that in folding a sheet as hereinbefore described the articles as folded may be placed in a superimposed regularly formed pile or stack, and that 40 it is unnecessary to place the folded articles in any particular manner in the pile or

stack, and without regard to the way or arrangement the articles are in the pile the feature of providing a pile or stack from which one article at a time is present, and that at the same time, in removing an article from the pile the said article will automatically unfold or partially so, so that it is substantially ready for use. 45

What is claimed is:—

1. An element designed for use in a dispensing package, wherein the folded sheets are superimposed one upon the other, comprising the following structure, namely a folded sheet of material, as an article of manufacture, including a blank initially folded along a median line to present a double half sheet, again folded along lines parallel to the median line, reversely to opposite sides of the double half sheet, and finally folded on a transverse median line to present double thickness coextensive tabs on opposite sides along one longitudinal edge of the sheet. 55

2. An element designed for use in a dispensing package, wherein the folded sheets are superimposed one upon the other, comprising the following structure, namely, a folded sheet of material, as an article of manufacture, including a blank initially folded along a median line to present a double half sheet, again folded along lines parallel to the median line, reversely to opposite sides of the half sheet, and finally folded on a transverse median line to present double thickness coextensive tabs on opposite sides along one longitudinal edge of the article, the portions between the fold lines being double thickness throughout. 65

In testimony whereof I affix my signature.

EMIL J. HANSEN.
